UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 27,181, dated June 8, 1897.

Application filed April 23, 1897. Serial No. 633,544. Term of patent 3½ years.

To all whom it may concern:

Be it known that I, HARRISON H. ROUNTREE, a citizen of the United States, and a resident of Chicago, in the county of Cook, State of Illinois, have invented and produced a new and original Design for Sprocket-Wheel and Driving-Chain Guards for Bicycles, of which the following is a specification.

At the front end of a guard or shield of my design is an opening which is defined by a ring or annulus A². Said ring or annulus is connected with the marginal frame A by an open-work web A³, which forms a scroll and extends a short distance rearward from said ring or annulus.

I claim—

The design for a sprocket-wheel and driving-chain guard or shield for bicycles, substantially as herein shown and described.

In testimony that I claim the foregoing as my invention I hereunto set my hand, this 19th day of April, 1897, in the presence of two witnesses.

HARRISON H. ROUNTREE.

Witnesses:

BLANCH DOUGLASS,
I. MEYER.
